UNITED STATES PATENT OFFICE

148,737

DESIGN FOR A FOUNTAIN PEN DESK STAND

Edward J. Vogel, Belleville, N. J.

Application July 3, 1946, Serial No. 131,293

Term of patent 3½ years

(Cl. D74—1)

To all whom it may concern:

Be it known that I, Edward J. Vogel, a citizen of the United States, residing at Belleville, in the county of Essex and State of New Jersey, have invented a new, original, and ornamental Design for Fountain Pen Desk Stands, of which the following is a specification, reference being had to the accompanying drawing, forming a part thereof.

In the drawing:

Figure 1 is a top plan view of a fountain pen desk stand showing my new design, and

Figure 2 is a side elevation thereof as seen from the right of Figure 1.

The essential features of my design reside in a desk stand having a base comprised of a pair of juxtaposed plates of contrasting color, the upper plate being transparent, in combination with the configuration of the supporting legs, all as illustrated.

I claim:

The ornamental design for a fountain pen desk stand, as shown and described.

EDWARD J. VOGEL.
